US0D1033657S

(12) **United States Design Patent** (10) **Patent No.:** **US D1,033,657 S**
(45) **Date of Patent:** **** Jul. 2, 2024**

(54) **DUAL-ARM RETENTION SLING**

(71) Applicant: **ARMBIE LLC**, Tulsa, OK (US)

(72) Inventor: **Christian Osse**, Tulsa, OK (US)

(73) Assignee: **ARMBIE LLC**, Tulsa, OK (US)

(**) Term: **15 Years**

(21) Appl. No.: **29/771,106**

(22) Filed: **Feb. 19, 2021**

(51) **LOC (14) Cl.** **24-04**

(52) **U.S. Cl.**

USPC **D24/190**

(58) **Field of Classification Search**

(57) **CLAIM**

The ornamental design for a dual-arm retention sling, as shown and described.

DESCRIPTION

FIG. 1 is a front, top perspective view of the dual-arm retention sling, showing the new design;

FIG. 2 is a front elevational view thereof;

FIG. 3 is a rear elevational view thereof;

FIG. 4 is a right-side elevational view thereof;

FIG. 5 is a top plan view thereof;

FIG. 6 is a front elevational view thereof, in use;

FIG. 7 is a rear elevational view thereof, in use;

FIG. 8 is a left-side elevational view thereof, in use;

FIG. 9 is a right-side elevational view thereof, in use; and,

FIG. 10 is a top plan view thereof, in use.

The broken lines depict parts of the dual-arm retention sling that form not part of the claimed design and environment that forms no part of the claimed design.

1 Claim, 10 Drawing Sheets
